UNITED STATES PATENT OFFICE

ROSE FEINTUCH, OF BROOKLYN, NEW YORK, ASSIGNOR TO ASSOCIATED MERCHANTISING CORPORATION, OF NEW YORK, N. Y., A CORPORATION OF NEW JERSEY

DESIGN FOR A DRESS

Application filed December 28, 1931. Serial No. 42,257. Term of patent 3½ years.

To all whom it may concern:

Be it known that I, ROSE FEINTUCH, a citizen of the United States, and a resident of New York, borough of Brooklyn, in the county of Kings and State of New York, have invented the new, original, and ornamental Design for a Dress, of which the following is a specification.

Reference is had to the accompanying drawings, forming part thereof, wherein—

I claim:

The ornamental design for a dress substantially as shown.

ROSE FEINTUCH.
